UNITED STATES PATENT OFFICE.

PHILIP D. PARSONS, OF PHILADELPHIA, PENNSYLVANIA, ASSIGNOR TO SCOTT PAPER COMPANY, A CORPORATION OF PENNSYLVANIA.

APPARATUS FOR SEALING PACKING-CASES.

1,273,531.

Specification of Letters Patent. Patented July 23, 1918.

Application filed February 9, 1917. Serial No. 147,664.

To all whom it may concern:

Be it known that I, PHILIP D. PARSONS, a citizen of the United States, and resident of Philadelphia, county of Philadelphia, 5 and State of Pennsylvania, have invented an Improvement in Apparatus for Sealing Packing-Cases, of which the following is a specification.

In the art of packing goods for shipment, 10 a packing case or carton made of fiber, cardboard or similar material sealed by suitably formed flaps and an adhesive, is now employed in many instances when previously it was thought necessary to use a 15 nailed wooden case or box. My invention relates to an improved means for facilitating the sealing of such fiber packing cases or cartons.

The object of my invention is to provide 20 a fiber packing case sealer which can be operated to insure speedy and reliable sealing of packing cases with a minimum consumption of time in and labor of handling.

A further object is to provide a fiber 25 packing case sealer of simple construction and having a minimum of wearing parts.

My object is also to provide a suitable 30 machine into which a filled carton or case may be placed after the top flaps have been cemented and folded in sealed position and carton inverted, so that the weight of the same will insure retention of the flaps, and whereby further, the bottom flaps (now on top) may also be cemented and folded into 35 sealing position and carton subjected to spring pressure from above and below while suitably supported laterally; further in employing, in said machine, means for facilitating the uptilting of the sealed carton to enable it to be grasped at one end 40 and upturned out of the pressure applying means.

My invention consists of certain improvements in fiber packing case sealers where- 45 by the above and other objects are attained, said improvements comprising certain organization and combination of parts which are fully described hereinafter and more particularly defined in the claims.

50 For the purpose of illustrating my invention, I have shown in the accompanying drawings the embodiment thereof which is at present preferred by me, since the same is in form to give satisfactory and reliable

results, but it is to be understood that the 55 several instrumentalities of which my invention consists can be variously arranged and organized and that my invention is not limited to the precise arrangement and organization of these instrumentalities as 60 herein shown and described.

Referring to the drawings; Figure 1 is a diagrammatic illustration of a plurality of stages in filling and sealing a fiber carton or packing case; Fig. 1^a is a perspective 65 view of one of the cartons before sealing; Fig. 2 is a side elevation of the sealer, together with the feed and discharge tables; Fig. 3 is a sectional plan view of the sealer on line x—x of Fig. 5; Fig. 4 is an elevation showing the means of applying power to close the lid of the sealer; Fig. 5 is a sectional side elevation of sealer taken on line y—y of Fig. 6; Fig. 6 is a vertical transverse section of the sealer on line z—z 75 of Fig. 5; and Fig. 7 is a plan view of one of the corners of the lid.

Fig. 1^a illustrates the packing case or carton which is to be delivered to the operatives for filling and is shown with both top 80 and bottom flaps open and unsealed, B denoting the bottom flaps of the case and T, the top flaps. At 2, the bottom flaps have been folded under but not sealed and the case has been filled with goods. At 3, the 85 top flaps are folded down and sealed with cement. At 4, the case is turned over and the bottom flaps exposed. At 5, the bottom flaps are sealed. After the adhesive has set, the case is turned under side up as 90 6 (Fig. 2) and the operation is complete.

To effect the above operations efficiently, I employ a combination of elements. These may be briefly stated as follows: 7 is a suitable table on which the filled cases or cartons are supported with their bottom flaps turned under, and over which table they are moved to the sealing machine proper indicated at 12. The end table 7 next to the sealing machine constitutes a delivery stage 100 9 having side guides 8 made in the form of sheet metal wings secured at each side of the frame adjacent to the sealing machine. The object of these wings 8 is to properly position the case or carton in respect to 105 alinement with the sealing machine into which it is to be delivered. From the sealer 12, the sealed cases or cartons are delivered

to a discharge or delivery table 13, of any desired form, and from which they are finally delivered for shipment.

The sealer 12 consists of a bottom structure 15, a hinged lid structure 15^a and suitable laterally inclosing and supporting frames 23. The bottom structure 15 is built up of inclosing side angle irons 17, and end angle irons 18 which form a rectangular frame, and a T iron 14 extending from the center of one side of the rectangular frame to the center of the other side and riveted thereto. The T iron 14 has a plurality of sheet metal spring strips 19 riveted to it, whose ends extend equally on either side of the supporting T iron and are so formed or curved that their free ends are normally higher than their fixed center parts. These strips form the floor portion of the bottom structure and it is apparent that when their ends are forced downward by pressure of the carton there will be a resulting counter pressure upward to close the flaps. The bottom structure and floor portion, so formed, is adapted to receive the case to be sealed as shown in the drawings.

The supporting structure comprises six upright T irons 16, three at the front of the sealer and three at the rear. The bottom structure 15 is riveted or bolted to the said supporting T irons, the connection being made with the side irons 17.

The lid structure 15^a is suitably hinged to the supporting structure and is built in a manner similar to the bottom structure. Angle irons 20 are riveted together to form a rectangular frame and from the center of one side of the rectangular frame to the center of the other side is riveted a T iron 21. To this T iron are riveted a number of sheet metal strips 22 which project equally on either side of the T iron so that their free ends extend close to the angle irons 20 forming the ends of the lid, and are below the plane of T iron 21. These sheet metal strips form the roof of the lid and as noted are formed so that their free ends are in a position lower than their center or fixed portions riveted to the T iron 21. This construction results in a spring action which exerts pressure downward upon the flaps of the carton. The lid as described is adapted to fit over the top of the packing case and when properly secured to exert a downward spring pressure on the same to hold the flaps in fixed position while the adhesive is setting.

The lid structure 15^a is secured to the T irons 16 of the supporting structure by means of three hinge lugs 20^a on the lid which are adapted to rotate on a hinge rod 20^b about which the lid may be swung. To hold the lid in its open position just beyond the vertical, the center hinge lug 20^a engages a stop lug 20^c secured to the supporting

structure. To clamp the lid in its closed position, there is provided a toggle clamping lever 27, its upper member 28 adapted to fit over a projecting lip 29 at the front edge of the lid. The lower member 30 of the toggle lever has one end hinged to the middle upright iron 16 of the supporting structure. Throwing out the lower end of lever 30, raises the upper end of lever member 28 and releases the clamping pressure so as to enable said member to be swung clear of the lid to release it. In clamping the lid, the lever member 28 is placed in contact with the projecting lip 29 of the lid and the throwing down of the lever 30 exerts a downward pull on the lid and clamps it in position.

The supporting structure is suitably braced by diagonal braces 16^b and end braces 16^a. At front and rear, between the center and end T irons 16, the case or carton is held in position by the sheet iron plates 36 riveted to the front and rear bottom side angle irons 17. These plates have their upper ends free and are adapted to exert a pressure inward on the packing case to prevent too much looseness and also to centralize the case under the lid.

31 designates two push rods which extend vertically upward through holes in one of the end angle irons 18 forming part of the bottom structure 15, and capable of sliding therein. The rods 31 are joined at the bottom by a cross bar 32 connected to a suitably pivoted treadle lever 33. Pressing the treadle 33 downward, causes the rods 31 to rise and in consequence raises one edge of the case which is resting above them on angle iron 18, thereby enabling the fingers to be inserted under the case or carton to lift it.

While the sealer may be accurately proportioned to receive cases or cartons of definite size, it is desirable to provide capacity for some adjustment to suit small variations in dimensions of the cases. By properly supporting the sides of the case the pressure applied in sealing the top and bottom flaps is effective without causing a bulged condition of the case. The lid 15^a is preferably formed of the four angle irons 20, adjustably connected at the corners; and this is provided for by the triangular plates 23 bolted to the angle irons by bolts 26 (Fig. 7). The plate 23 has two sets of slotted holes, 24 and 25, whose directions of length are at right angles, as shown, one receiving bolts 26 for the end angle irons 20 and the other set receiving similar bolts for the side angle irons 20. By this means the rectangular size and shape of the lid may be slightly adjusted and thus made to snugly fit over the top of the cases, even though they varied slightly.

At the lower or bottom of the case sup-

porting part, the width may be adjusted by having the end irons 18 provided with bolts 34 which pass through transverse slots 35 in the ends of the side angle irons 17. By 5 loosening these bolts 34 the two sides (16, 17 and 36) may be adjusted relatively toward or from each other to suit the width of the cases or cartons to be sealed.

The adhesive to be employed may be 10 varied to suit the requirements, but I have found the most satisfactory material to employ is a reasonably fluid silicate of soda, which is easily applied and quickly sets. This substance has body enough to insure 15 perfect union of the overlapping flaps; and by excluding the air when the pressure is applied by the sealer and holding the parts until the adhesive sets, the atmospheric pressure insures a perfect and strong adhesion 20 of the flaps during the hardening of the silicate.

In operation, the sealer is used as follows:—The fiber case when filled, is received at the landing stage 9 with top side 25 T up, the bottom flaps B folded under but not sealed. The operator then applies the adhesive to the top flaps to seal them and turns the case over into the sealer and this brings the bottom flaps B to the top. Adhesive is then applied to the bottom flaps, they are fastened down, after which the lid is closed down and clamped. The clamping pressure is applied for a suitable time, usually about two minutes, during which 30 time it will be noted that the function of the springs 22 and 19 is to hold the flaps in close contact while the adhesive is setting. The springs being yielding, apply the pressure where and to the extent needed. 35 When the necessary time has elapsed, the operator releases the clamping pressure by throwing up lever 30 and disengaging lever 28. The lid is then swung upward and back. Pressure may now be applied to the treadle 40 45 33 to cause the rods 31 to raise one end of the case, which may then be grasped and turned over upon the discharge table 13, as indicated at 6. The sealer 12 is now ready to repeat the sealing operation.

It will be apparent that in sealing fiber 50 packing cases with adhesive there is a certain minimum amount of time which must be consumed in sealing each case and this minimum is that required for the adhesive 55 to set. The additional time required is that utilized in handling the case. My invention as above described reduces the time of and labor in handling while also holding the case securely during the interval when the adhesive is setting and thus securing reliable 60 sealing. The time and labor are reduced, first, by having a supply of cases to be sealed delivered in close proximity to the sealer; second, by providing means for quickly 65 clamping the lid; third, by enabling the lid

quickly to be swung clear; and fourth, by arranging a treadle operated device to facilitate the discharging the sealed cases from the sealer. It should be noted here that by slight modifications, my constructions may 70 be made adjustable and suitable to seal cases of various dimensions.

It will now be apparent that I have devised a novel and useful construction which embodies the features of advantage enumerated as desirable in the statement of the invention and the above description, and while I have in the present instance shown and described the preferred embodiment thereof which is best suited to give satisfactory and 80 reliable results in practice, it is to be understood that the same is susceptible of modification in various particulars without departing from the spirit or scope of the invention or sacrificing any of its advantages. 85

Having now described my invention what I claim as new and desire to secure by Letters Patent is:—

1. In a device of the character stated, the combination of a bottom structure having 90 a supporting portion capable of exerting a spring action upward, a hinged lid structure having a portion capable of exerting a spring action downward, vertical spring plates suitable for holding the sides of a 95 case to be sealed in fixed relation between the said lid and said bottom structures, and means for clamping the lid structure in the closed position.

2. In a device of the character stated, the 100 combination of a bottom structure having a supporting portion capable of exerting a spring action upward, a lid hinged structure having a portion capable of exerting a spring action downward, and means suitable for holding the sides of a case to be sealed in fixed relation between the said lid and said bottom structures, said bottom structure comprising a rectangular frame, a cross iron securely fastened from the 110 center of one side of said frame to center of opposite side, a plurality of sheet metal springs securely fastened in the middle to said cross iron and extending on either side with their free ends above the plane of said 115 cross iron, and independently operative to press upon the case to be sealed, said lid structure comprising a rectangular frame, a cross iron fastened from the center of one side of said frame to center of opposite side, 120 a plurality of sheet metal springs fastened in the middle to said cross iron and extending on either side with their free ends below the plane of said cross iron, and independently operative to press upon the case 125 to be sealed.

3. In a device of the character stated, a rectangular bottom structure having a fixed floor portion having a plurality of springs each capable of exerting an independent 130

spring action upwardly at a plurality of separate places near each end, combined with a rectangular lid structure also provided with a plurality of springs each capable of exerting 5 an independent spring action downwardly at a plurality of separate places near each end, and suitable means for holding the lid in fixed relation to the bottom for clamping a case to be sealed between them, the 10 said springs each directly pressing upon the case to be sealed and providing independent action.

4. In a device of the character stated, a rectangular bottom structure having a fixed 15 floor portion having a plurality of springs each capable of exerting an independent spring action upwardly at a plurality of separate places near each end, combined with a rectangular lid structure provided 20 with a plurality of springs each capable of exerting an independent spring action downwardly at a plurality of separate places near each end and said lid structure also having means for adjusting its linear dimensions 25 to suit cases of varying dimensions, and suitable means for holding the lid in fixed relation to the bottom for clamping a case to be sealed between them, the said springs each directly pressing upon the case to be sealed and providing independent action.

5. In a device of the character stated, the combination of a main frame having upright sides at front and back, a bottom frame 35 separate from the main frame for supporting the case to be sealed said bottom adjustably secured to the sides of the main frame so as to permit said sides of the main frames to be adjusted relatively toward or 40 from each other to vary the space for receiving the case, a lid hinged to the main frame and adjustable as to its width in the direction transverse to the hinge axis to correspond to the adjustment of the bottom 45 said lid having spring pressure plates on its under side to directly press upon the case, and means for locking the lid in closed position above the bottom frame.

6. In a device of the character stated, the 50 combination of the main frame having sides,

a bottom frame, a lid hinged to the main frame and having spring pressure plates on its under side providing free ends to directly press upon the case to be sealed, said lid having four angle iron bounding irons 55 jointed at the corners by adjustable corner plates whereby the area of the lid may be slightly varied, and means for clamping the lid in position upon the main frame over the bottom frame. 60

7. In a device of the character stated, a main frame having a plurality of upright irons at each side, combined with a bottom frame between said sides and secured to them, side sheet plates fixedly secured at their lower parts adjacent to the bottom frame, and extending upward above the bottom and between the upright irons of the respective sides and free at their upper ends to form flexible sides to the main frame, a lid hinged 70 to the top of the side irons of one side and having spring pressure plates on its under side presenting free ends, and means for clamping the lid to the other side upright irons and in position parallel to the bottom 75 frame.

8. In a device of the character stated, a main frame having a plurality of upright irons at each side, combined with a bottom frame between said sides and secured to 80 them, said bottom frame provided with spring pressure plates on its upper side, said plates presenting free ends, side spring plates fixedly secured at their lower parts adjacent to the bottom frame and extending upward above the bottom and between the upright irons of the respective sides and free at their upper ends to form flexible sides to the main frame, a lid hinged to the top of the side irons of one side and having spring pressure plates on its under side 85 presenting free ends, and means for clamping the lid to the other side upright irons and in position parallel to the bottom frame. 90

In testimony of which invention, I here- 95 unto set my hand.

PHILIP D. PARSONS.
